(74) Attorney, Agent, or Firm — Alyssa K. Sandrowitz, Esq.; Kevin J. Aiken, Esq.

(57) **CLAIM**

The ornamental design for a sprocket, as shown and described.

DESCRIPTION

FIG. 1 is a front perspective view.

FIG. 2 is a front elevation view.

FIG. 3 is a side elevation view.

FIG. 4 is a top plan view; and,

FIG. 5 is a rear elevation view.

The broken lines shown on the sprocket are included for the purpose of illustrating portions of the sprocket which form no part of the claimed design.
